UNITED STATES PATENT OFFICE.

WILLIAM C. FARNUM, OF ARLINGTON, VERMONT, ASSIGNOR TO WYCKOFF, SEAMANS & BENEDICT, OF ILION, NEW YORK, A CORPORATION OF NEW YORK.

TYPE-WRITING MACHINE.

No. 904,688.

Specification of Letters Patent.

Patented Nov. 24, 1908.

Application filed April 9, 1903. Serial No. 151,823.

To all whom it may concern:

Be it known that I, WILLIAM C. FARNUM, citizen of the United States, and resident of Arlington, in the county of Bennington and State of Vermont, have invented certain new and useful Improvements in Type-Writing Machines, of which the following is a specification.

My invention relates more particularly to means for arresting the paper-carriage and for locking the escape-wheel and rocker-arm at the end of a predetermined line; to means for releasing the paper-carriage and escape-wheel and rocker-arm so that additional characters may be printed beyond the predetermined point after the carriage has been once arrested and the escape-wheel and rocker-arm have been locked; to a final carriage-stop and a final lock for the escape-wheel and rocker-arm; to a bell mechanism to give warning of the approach to the end of the printing line; to means for arresting the carriage on its return movement at a predetermined point so as to give a predetermined margin; to means for enabling the carriage to write within the predetermined margin; to improved constructions of line, margin and carriage-stops; to means for adjusting the paper and platen through minute distances in the direction of the printing line; to means for adjusting the relation between the carriage-rack and pinion; to means for connecting the carriage-truck and the carriage-rack; and to various other improvements and combinations of devices hereinafter set forth.

While I have shown my invention as applied to the typewriter known as the Remington No. 6 machine, it will of course be understood that the improvements may be embodied in other styles or types of machines without departing from the spirit of my invention.

In the accompanying drawings, Figure 1 is a top plan view of the machine, showing at the rear thereof my improvement in plan. Fig. 2 is a sectional elevation of the machine taken on the line *x x* of Fig. 1. Fig. 3 is a rear elevation of the machine. Fig. 4 is a fragmentary sectional view looking towards the right and in the rear of the machine, showing a portion of the carriage arresting means and of the escape-wheel and dog-locking means. Fig. 5 is a perspective view 55 of a portion of the escapement or carriage-

feed mechanism. Fig. 6 is a fragmentary rear view of a portion of the escape-wheel and dog-rocking arm, with a portion of the means for locking the same. Fig. 7 shows the line stop on the stop-rack, the connection 60 with the stop-rack being such as is common to all the stops. Fig. 8 is a rear view of the right-hand portion of the means for the longitudinal adjustment of the carriage-rack. Figs. 9, 10, 11 and 12 are detail views of the 65 same, Fig. 10 being a sectional view on the line *y y* of Fig. 8. Fig. 13 is a perspective view of the stop-rack bar and stops and Fig. 14, a view of the carriage-feed rack bearing.

Throughout the drawings various parts 70 have been omitted or broken away in order to more clearly disclose my improvements.

Like numerals of reference designate like parts in the various views.

1 designates the base of the machine 75 frame, 2 the frame uprights or posts, 3 the top-plate thereon, 4 the lugs supporting the rear carriage rail 5, on which run the rear wheels 6, mounted in the truck 7, to which is connected the swinging platen-carrier 8; 80 9 being the platen therein and 10 the front wheel running on the shift-rail 11, as is customary in the Remington No. 6 machine. The carriage, as is usual, is connected to the spring-drum or box 12, by means of the 85 band 13. The type-bars 14, mounted in hangers 15, are connected by the connecting rods or wires 16 to the key-levers 17, fulcrumed at 18 and mounting at their forward ends the key-buttons or caps 19. Each 90 depression of a key-lever 17, or of the space-bar 20, depresses the universal bar 21 connected by the connecting wires 22 to the laterally extending arms 23, which are attached to the horizontal arm 24 of a vibrating member or rocker 25, this last in turn being pivoted in the supplemental frame 26 depending from the top-plate 3.

The vertical arm 27 of the rocker 25 is bifurcated at the upper end, as shown most 100 clearly in Fig. 5, and the rear prong or fork 28 of the bifurcation is bent substantially at right angles to arm 27 and to the left thereof, viewed from the rear, while the forward prong or fork 29 is similarly bent to 105 the right.

The bent prong 29 actuates the train of mechanism causing the letter-space feeding movement of the carriage, and which, as it is claimed and described at length in my ap- 110

lication Serial No. 148,942, filed March 21, 1903, it is unnecessary to describe with any great degree of particularity. The letter-space feeding mechanism acts upon the carriage truck 7 through the rack 30, attached thereto in a manner hereinafter described; and the pinion 31. The said pinion 31 is fixed upon the forward end of shaft 32, which shaft carries at its rear end the toothed escape-wheel 33 having teeth 33^a, and is supported in bracket 34 on the top-plate 3. The bracket 34 also serves as a bearing for the dog-shaft 35 (Fig. 3) on which is pivoted the holding dog 36 and the loose dog 37 controlled thereby, the holding-dog 36 having on its lower face the teat or lug 38 (Figs. 3 and 5) which plays in a slot 39 in the horizontal vibratory piece 40. Piece 40 is pivoted on the vertical shaft 41 which has its bearings in the bracket 34 and top plate 3. The piece 40 is held normally against its rear stop 42 by the spring 43, and is turned clock-wise against the tension of said spring 43 by the fork 29 of arm 27 acting on the opposite end of piece 40 whenever the rocker-arm 27 is rocked forward under action of the finger-keys 19 or space-key 20. When the finger-key or space-bar is released, the spring 43 tends to return the piece 40 against stop 42, and this vibratory action of the piece 40 between stops 42 and 44 controls the escapement or letter-space feed movement through the teat 38 of holding-dog 36, as explained more in detail in my aforesaid pending application Serial No. 148,942. It will be understood, therefore, that whenever the rocker-arm 27 is held from forward movement under the key action, no motion of the escapement mechanism can take place nor can the type-bar print, since the universal bar 21, connected as described to the rocker 25 and rocker-arm 27, prevents the depression of key-levers 17. The mechanism for accomplishing this result will now be explained. Supported in the lugs 45 at the rear of the top-plate is the guide-rod 46, which is embraced by the lug 47 extending rearwardly from the carriage-truck 7; as is usual. Pivoted on the guide-rod 46 and in proximity to the supporting lugs 45 are the end pieces 48 joined by the cross-piece 49, the whole forming an integral U-shaped piece or rocking bar with bearings on guide-rod 46, as appears most clearly in Figs. 1 and 3. Loosely pivoted in the tops of end pieces 48 is the stop-rack 50, carrying bell-trip 51, line-stop 52 and margin-stop 53. The stop-rack 50 is a square rod having teeth 54 on one corner only (the upper right-hand corner as viewed in Fig. 7), and has a horizontal slot 55 cut in its front vertical surface. Each of the stops 51, 52 and 53 has a horizontal lip 56 entering this slot 55, and each is prevented from withdrawing from the slot by the rear up-

right portion 57 of the stop. The rear upright portion 57 provides a bearing for the pivot 58 of the spring mounted locking member 59. On depressing the trip-piece 60 of the locking member 59, the stop 51, 52 or 53 may be unlocked from the stop-rack 50, and moved to any desired position, as indicated by the usual scale on the top of stop-rack 50. The mechanism thus described is common to all the stops 51, 52 and 53, and it will be understood that while each is freely movable longitudinally of the stop-rack 50, it cannot be removed nor knocked loose therefrom without dismembering the stop.

Forward of the stop rack 50, the bell-trip stop 51 is provided with the usual pivoted bell-trip cam 61 (Figs. 1 and 13). The confining lip 55 of the margin-stop 53 broadens out forwardly into a plate 62 (Figs. 1 and 13) having a camming face 63 at the left side and an upwardly projecting pin 64 at the right side, as viewed in Figs. 1 and 13. The forward portion 65 of the line-stop 52 has a slot 66 (Figs. 4, 7 and 13) at about the vertical center and extending to within a short distance of the left vertical face. At the right side of 65 is the camming face 67. Fixed in the rearwardly projecting guide lug 47 is the vertical rod 68 which serves as a bearing for the carriage-stop 69. This latter is in the form of a collar with a top rim 70, and is normally held in contact with the guide lug 47 by the spiral spring 71, which is confined between the screw top 72 and the rim 70, as shown in Figs. 2 and 4.

Referring now to Figs. 1, 3 and 4, 73 denotes a pin projecting from the lower end 48^a of the right-hand end-piece 48 and adapted to be embraced by the bifurcated, upturned end 74 of the horizontal locking bar 75. The locking bar 75 has a forwardly projecting branch or arm 76 at the end of which is the bearing 77, which is in the form of a screw screwed into the top-plate 3. The locking bar is normally held in contact with the top-plate 3 by the spring 78, and has, near the upright end 74, a slot 79 affording play for the guiding and limiting screw 80, screwed into the top-plate 3. The left-hand end of the locking bar 75 carries a locking teat 81 extending longitudinally of the bar 75 and adapted to lock the rear prong 28 of rocker arm 27, and a forwardly extending locking teat 82 adapted to lock the teeth 33^a of the escape-wheel 33. The locking member or bar 75 is adapted to be swung upward away from the top plate in the manner presently to be explained. In the upward swinging movement of the bar the screw 77 serves as a pivot therefor, the bar proper being connected with the pivot 77 by the arm 76. The bar 75 is prevented from sliding on the top plate or rotating horizontally on the pivot 77 by the screw 80,

the head of said screw serving to limit the upward swinging movement of the bar 75 about the pivot 77.

The operation of the carriage-stop and line and margin-stop mechanisms will now be described. Suppose the carriage to be at that point in its forward travel shown in Fig. 1, and the bell-trip 51, line-stop 52 and margin stop 53 to be arranged on the stop-rack 50 as shown in said Fig. 1. As the carriage approaches the bell-trip 51, the rim 70 of carriage-stop 69 will contact with the camming surface 61 of the bell-trip, and riding across the cam towards its highest part 15 at the left will gradually depress the bell-trip, and as the bell-trip 51 is locked fast to stop-rack 50, the said stop-rack will be swung about its pivots in arms 48 in a clockwise direction, as viewed from the left of the machine. The stop-rack 50, in its movement about its pivot, raises the bell ringer finger 83 screwed on the stop-rack and carrying bell-hammer 84, so that when the lip 70 has passed the cam 61, in the course of the 20 carriage letter-space feeding movement, the stop-rack 50 returns to its normal position and the bell ringer 84 contacting forcibly with the bell 85 on the back of the spring-box 12, warns the operator of the approach 25 to the end of the printing line. Having cleared the bell-trip, the rim 70 of the carriage stop 69 will next contact, in the course of the carriage letter-space feeding movement, with the cam face 67 of the line-stop 30 52 below slot 66, gradually forcing the line-stop towards the rear. As seen in Fig. 4, this rearward movement of the line-stop 52 also forces rearwardly the stop-rack 50 on which it is supported, and as the stop-rack 35 50 is pivoted in the upper ends of arms 48, the latter will revolve about their bearings on the guide-rod 46 and the lower end 48^a of the right-hand end-piece, carrying the pin 73, will be revolved towards the front of 40 the machine until it attains the position shown in Fig. 4. The bifurcated arm 74, embracing the pin 73, will be moved upwardly and forwardly by the pin 73 and the locking bar 75 raised from the top-plate 3 45 against the pressure of the spring 78, said bar swinging upwardly about the pivot screw 77 until arrested by the head of the stop screw 80. The heads of the screws 77 and 80 are arranged at a sufficient distance above the top 50 plate to permit the bar or member 75 to be raised or moved upward to operative position before being arrested. The force exerted on the bar or member 75 through the pin 73 tends to slide said member forward on 55 the top plate but any sliding movement is prevented by the stems of the screws 77 and 80 and consequently the member 75 is raised from the top plate by the force applied through the pin 73, the raising or upward movement of the member 75 continuing un-

til said member is arrested by the head of the screw 80.

As will be seen in Fig. 3, the locking teats or lugs 81 and 82 lie normally in a plane below the prong 28 of the rocker arm 27 and the teeth 33^a of the escape-wheel 33. The upward movement of the locking bar 75 raises the locking teats to the position shown in Figs. 4 and 6, and a subsequent depression of a finger-key 19 or space-bar 20 will 70 bring the prong 28 into contact with the locking teat 81, thus preventing the forward movement of the rocker-arm 27 and the actuation of the feed-dogs 36 and 37 by prong 29, as previously explained. At the same time the locking teat 82 is interposed 75 between the two lowermost teeth 33^a of the escape-wheel 33 and the locking bar 75 having reached the limit of its upward movement as determined by the stop 80, the train 80 of mechanism connecting said locking-bar with the line-stop 52 is locked and the line-stop 52, being locked from further rearward movement, locks the carriage, through the rim 70 of the carriage-stop 69, from further 85 movement in the feeding direction. Pressure on the spring-mounted release rod 86, common in the Remington No. 6 machine, causes its rear upturned end 87, acting upon the finger 88 (Fig. 3), to turn the stop-rack 90 95 50 in its bearings in the direction of the arrow in Fig. 4, until the rim 70 of the carriage-stop enters the slot 66 in the forward portion 65 of stop 52. The carriage stop 69 being spring-controlled, the stop 100 rim 70 will enter the slot 66 readily, and as soon as this occurs, as will be understood from a consideration of Fig. 4, arm 48^a will be free to return towards the rear of the machine and the locking bar 75 will drop back 105 onto the top-plate 3, releasing the escape-wheel 33 and rocker-bar 27. The rim 70 having entered slot 66, as seen in Fig. 2, the carriage will be free to move an additional 110 number of letter spaces in the printing direction, as determined by the longitudinal dimension of slot 66, (Figs. 1 and 13). When the left-hand end of the slot 66 (which is a camming surface, as shown by the dotted line in Fig. 1) is reached, the line-stop will again be forced rearwardly by the stop rim 70, stop arm 75 will be raised and the parts locked as before; but since the stop rim 70 remains in slot 66, a further release 115 is prevented, and the final end of the line is 120 thus accomplished.

On retracting the carriage, the line locking mechanism returns to its normal position as soon as the stop rim 70 is withdrawn from contact with the left-hand end of the slot 66. 125 When in its return movement, having passed the liftable cam 61, the carriage through the stop-rim 70, contacts with the cam surface 63 of margin-stop 53 (Figs. 1 and 13) the latter is forced to the rear until further movement 130

is prevented by the limiting pin 80, precisely as in the case of the line-stop in the forward movement of the carriage, and the margin is thus determined. When it is desired to write within the margin, pressure upon the release-rod 86 will as before cause the stop-rack 50 to revolve about its pivots, and the plate 62 of margin-stop 53 will be brought below the stop rim 70, allowing the carriage 10 to be retracted to a final position as determined by the contact of the stop-rim 70 with the vertical pin 64. Overthrow of the stop-rack 50, when actuated by release-rod 86, is prevented by the spring stop 88, screwed to the stop-rack, contacting with guide-rod 46 (Fig. 4).

The carriage-feed rack adjustments and mountings will now be described. Referring more particularly to Figs. 1, 3, 8 and 14, 20 the feed-rack 30 has riveted to it at either end slotted brackets 89 and 90. The pivots 91 of the rear carriage wheels 6 are prolonged rearwardly at 92 to afford supports for the eccentric collar bearings 93. Check 25 nuts 94 hold the adjustable collars 93 in position, said collars being as will be seen in Fig. 14, eccentric with relation to their pivots 92. When the check nuts 94 are loosened the eccentric bearing collars 93 may 30 be adjusted by means of a wrench fitted into the slots 95 cut therein, so that the rack 30, the slots 96 of whose brackets 90 embrace said eccentric collars 93, may be maintained at any desired height with relation to pinion 35 31. Wear on the teeth may thus be compensated for and a ready adjustment afforded without interfering in any way with the carriage proper. Integral with rack bracket 90 is the arm 97 at the end of which is the 40 ring-like portion 98, and keyed within the ring 98 is the chambered bearing 99 (Figs. 9 and 10). It will be understood that 98 and 99 might be one piece, but for purposes of construction it is found more convenient to 45 turn and finish the bearing 99 and then key or pin it to the ring 98. The front face 100 of 99 is chambered at 101 to admit the collar-piece 102. The collar-piece 102 forms the bearing for the eccentric piece 103 carrying 50 on its front face the eccentric proper 104. The rear face 105 of the eccentric piece 103 is fluted or roughened as at 105, and chambered at 106 to admit the collar-piece 102. The front face of the chambered bearing 99 55 is likewise fluted or roughened so as to afford holding contact with 103. Pinned or otherwise fastened to the face of eccentric 104 is the handle-piece 107. Confined between the front face of eccentric-piece 103 and the rear 60 face of the handle-piece 107 and bearing on the eccentric 104 is the ring-like portion or eccentric strap 108 of eccentric rod 109.

As clearly appears in Fig. 10, the parts above described are maintained in operative 65 relation by the shoulder screw 110, spring

disk 111 and nut 112. Returning now to rod 109, it is seen to be pivoted at 113 to rod 114 under the restraining and guiding lug 115, projecting from ratchet bracket 90. Rod 114 is enlarged and squared at 116 where it 70 passes between the lugs 117 projecting from carriage-truck 7 (Figs. 1 and 3), the enlarged square portion 116 where it joins the cylindrical part of the rod 114 at the left (as viewed in Fig. 3) forming shoulders 118. 75 The rod 114 is threaded at its end to receive the check nuts 119, 120, for confining the spool 121, for which the under surface of carriage-lug 47 forms a half bearing. Fas- 80 tened in the head 122 of this spool, which normally abuts against the left-hand vertical face of lug 47, is one end of the coiled spring 123, the other end of which is in the sleeve or 85 slideable collar 124, which bears normally against lugs 117. The sleeve 124 is slideable on the cylindrical portion of the rod 114 at the left of the squared portion 116 as viewed from the rear. Normally said sleeve or slideable collar is maintained pressed against the shoulders 118 by the coiled spring 123. The 90 rod 114 is normally held in a fixed relation to the carriage by the spring 123, as will be clearly understood from an inspection of Figs. 1 and 3. The said spring 123, it will be perceived, maintains the spool head 122 95 in contact with the left-hand face of lug 47, and forces the rod 114 to the left by contact of the collar 124 with shoulders 118 on the rod 114. This movement of the rod con- 100 tinues until the collar 124 contacts with the lugs 117 on the carriage-truck 7. In assem- 105 bling, as soon as the parts are thus related the check-nut 119 is screwed up against the right-hand head of the spool 121, and locked by nut 120. This action, it will be under- 110 stood, establishes a normal fixed relation be- 115 tween the carriage, the rod 114, rod 109 and ring 108, so that when the handle 107 of the eccentric is revolved to the right or left a corresponding movement of the carriage to the left or right of the rack 30 will take place, the slots 96 in the bearing brackets 89 and 90 permitting considerable longitudinal play of the eccentric rack bearings 93, and thus the relation between the carriage and 115 platen on the one side and the rack 30 on the other, is altered. This movement may be so regulated as to make any desired point on the paper inserted in the machine coincide longitudinally with the printing point, thus 120 facilitating insertions and corrections.

When the carriage is suddenly stopped in its movement to the right or left, the spring 123 acts as a buffer, lessening and distributing the shock of the arrest on the carriage 125 rack and its pinion 31 which are constantly engaged, and the engaging teeth of which would be liable to breakage without a cushioning device, such as a buffer or spring. When the carriage is moving to the left and 130

is suddenly arrested, the lugs 117 act as stops for the left-end portion of the spring 123 but the carriage rack tends to move on to the left and pull the rod 114 with it. The nuts 5 119 and 120 on the right-hand end of this rod act against the spool 121 to urge it leftward and the flange 122 of the spool consequently presses leftward against the right-hand end portion of the spring 123. The result is that the spring is slightly compressed 10 and thus cushions the arrest of the carriage rack 30. If the carriage be suddenly arrested during its movement towards the right, the flange 122 of the spool 121 will serve as 15 a stop for the spring 123, the left-hand end portion of which spring will at this time be urged rightward by the shoulders 118 of the rod 114 acting against the sleeve 124.

It will be seen that I provide carriage 20 feeding devices comprising a rack and pinion which are constantly in mesh, the rack being adjustable radially of the pinion to vary the relation between the teeth of said rack and pinion, means also being provided 25 for varying the longitudinal relation between the rack and the carriage with which it is connected. Furthermore, it will be seen that the connection between the rack and the carriage comprises a mechanical connection 30 in the form of a double acting buffer device or compressible spring which is operative when the carriage is suddenly arrested during this longitudinal travel in either direction to cushion the shock of such arrest on 35 the carriage rack and lessen the liability of breakage of the teeth thereof as well as of the teeth of the coöperating pinion. Thus it will be perceived that the spring 123 serves as a double buffer, acting in either direction 40 of the carriage movement.

What I claim as new and desire to secure by Letters Patent, is:—

1. In a typewriting machine, the combination of a carriage, step-by-step feeding devices therefor, including a rack, dogs co-operative therewith, and a vibratory member or rocker operatively connected with said dogs, and means coöperating with the carriage to stop it positively from movement in 45 printing direction, said means also coöperating with the rack to lock it positively against movement and said means further coöperating with the vibratory member to lock it positively against movement.

50 2. In a typewriting machine, the combination of a carriage, step-by-step feeding devices therefor including a rack, dogs co-operative therewith, and a vibratory member or rocker operatively connected with said dogs, and line locking devices directly and positively coöperating simultaneously with said carriage, said rack and said vibratory member to lock each separately and positively.

55 3. In a typewriting machine, the combination of a carriage, step-by-step feeding de-

vices therefor including a rack, dogs coöperative therewith, and a vibratory member or rocker operatively connected with said dogs, and line locking devices directly and positively coöperating simultaneously with said carriage, said rack and said vibratory member to lock each separately and positively, said line locking devices being further operative to release or unlock said carriage, said rack and said vibratory member to permit 75 additional characters to be printed.

4. In a typewriting machine, the combination with a carriage and its escapement mechanism including an escapement wheel, dogs, and a dog actuating rocker arm, of a 80 rocking bar, means carried by the carriage to rock said bar, and means actuated by said bar to engage directly with and positively lock both the escapement wheel and the dog actuating rocker arm.

5. In a typewriting machine, the combination with a carriage and its escapement mechanism including an escapement wheel, dogs, and a dog actuating rocker arm, of a 85 rocking member, and means actuated by the rocking movement of said member to lock both the escapement wheel and the dog actuating rocking arm, said means comprising a member operative to engage both the escapement wheel and the rocker arm.

95 6. In a typewriting machine, the combination with a carriage and its escapement mechanism including coöperating rack and dog-operating members, of an actuating device on the carriage, a rocking bar adapted to be rocked thereby, and a locking bar actuated by said rocking bar to engage both the rack and dog operating members so as to lock the escapement.

100 7. In a typewriting machine, the combination with a carriage and its escapement mechanism including coöperating rack and dog-operating members, of an actuating device on the carriage, a rocking bar adapted to be rocked thereby, and a locking bar pivotally mounted on the top plate of the machine and movable by said rocking bar into position to engage both the rack member and the dog-operating member to lock the escapement.

105 8. In a typewriting machine, the combination with a carriage and its escapement mechanism including escapement dogs, an escapement wheel and dog actuating means, of an actuating device on the carriage, a 110 rocker bar adapted to be rocked thereby, and a locking bar movable by said rocker bar to bring a locking portion of said locking bar between the teeth of said escapement wheel and another locking portion of said locking bar into the path of the dog actuating means causing the locking of both the escapement wheel and the dog actuating means.

120 9. In a typewriting machine, the combination with a carriage and escapement devices 125

therefor including a feed rack, feed dogs, and actuating means for said dogs, of line locking mechanism comprising a locking bar supported normally on the top plate and having a pin and hole connection therewith; and devices operative to lift said bar from the top plate and cause it to lock said escapement devices at the end of the printing line.

10. In a typewriting machine, the combination with a carriage and escapement devices therefor including a feed rack, feed dogs and actuating means for said dogs, of line locking mechanism comprising a locking bar supported normally on the top plate and having a pin and hole connection therewith; and devices operative to lift said bar from the top plate and cause it to lock said escapement devices at the end of the printing line, certain of said last named devices being independently movable to unlock said bar to permit of the printing of additional characters in the line.

11. In a typewriting machine, the combination with the carriage, and step-by-step feeding devices therefor, including a rack, dogs, and a vibratory member or rocker operatively connected with said dogs, of line locking devices including a member operative to lock simultaneously against movement of said rack and said vibratory member by direct engagement with each other.

12. In a typewriting machine, the combination with the carriage, and step-by-step feeding devices therefor including a rack, dogs and a vibratory member or rocker operatively connected with said dogs, of line locking devices including a member having a lug adapted to enter the spaces between the teeth of said rack, said member being provided with another lug adapted to engage with said vibratory member or rocker to prevent movement thereof.

13. In a typewriting machine, the combination of a platen carriage; a stop member or contact thereon; a stop bar; an adjustable line stop or contact thereon; a frame pivoted at the rear of the machine and in which said stop bar is movably mounted; a locking bar or plate mounted on the machine below said pivoted frame and operated thereby; stop members on said locking bar or plate; escapement devices with which said last mentioned stop members are adapted to coöperate; and hand actuated means for moving said stop bar in said pivoted frame independently of movement by said pivoted frame, the independent movement of said stop bar causing said line stop and the stop member on the carriage to disengage from operative engagement.

14. In a typewriting machine, the combination of a platen carriage; a stop member or contact thereon; a stop bar; an adjustable line stop or contact thereon; a frame pivoted at the rear of the machine and in which said

stop bar is movably mounted; a locking bar or plate mounted on the machine below said pivoted frame and operated thereby; stop members on said locking bar or plate; and escapement devices with which said last mentioned stop members are adapted to co-operate.

15. In a typewriting machine, the combination of a platen carriage; a contact carried thereby; a frame pivoted on a fixed part of the machine; a stop bar pivoted in said frame and capable of being bodily revolved with said frame about the pivots of the latter, said stop bar also being capable of rotary movement about its own longitudinal axis; an adjustable bell-trip on said stop bar; a bell; and a bell hammer adapted to be actuated by the rotary movement of said stop bar, which movement is caused by the co-action between the adjustable bell trip and the contact on the carriage.

16. In a typewriting machine, the combination of a platen carriage; a contact carried thereby; a frame pivoted on a fixed part of the machine; a stop bar pivoted in said frame and capable of being bodily revolved with said frame about the pivots of the latter, said stop bar also being capable of rotary movement about its own longitudinal axis; an adjustable line stop on said stop bar; a locking bar or plate arranged below said stop bar and connected with the frame in which said stop bar is pivoted; stop members carried by said locking plate; escapement members with which said last named stop members coöperate to prevent letter space of the carriage when said stop bar is caused to revolve bodily about the pivots of the frame in which it is mounted; and means for revolving said stop bar on its axis and permitting additional letter space movements of the carriage after the latter has been prevented from moving in letter space direction.

17. In a typewriting machine, the combination of a platen carriage; a contact or stop thereon; a frame pivoted to a fixed part of the machine; a stop bar pivoted in said frame; a limiting stop for controlling the extent of movement of said frame; an adjustable stop or contact on said stop bar adapted to coöperate with the carriage stop to cause said frame to rotate about its pivots until arrested by said limiting stop, whereby further movement of the carriage is prevented; and a manually operated means to rotate said stop bar on its longitudinal axis to free the carriage and permit further letter space movements thereof.

18. In a typewriting machine, the combination of a carriage, a feed rack carried thereby and provided with elongated slots, a feed pinion, and eccentric bearings on said carriage coöoperating with the slots in said feed rack, said eccentric bearings being operable

to effect a relative adjustment between the feed rack and the feed pinion.

19. In a typewriting machine, the combination of a carriage, a feed rack carried thereby and provided with slots, a feed pinion, eccentric bearings on said carriage co-operating with the slots in said feed rack and operative to effect relative adjustment between said feed rack and said feed pinion, and means for effecting a longitudinal adjustment between said carriage and said feed rack.

20. In a typewriting machine, the combination of a carriage, a feed rack carried thereby and provided with slots, a feed pinion, eccentric bearings on said carriage co-operating with the slots in said feed rack and operative to effect relative adjustment between said feed rack and said feed pinion, and means for effecting a longitudinal adjustment between said carriage and said feed rack, said last recited means including an eccentric and a coöperating eccentric strap.

21. In a typewriting machine, the combination with a carriage and carriage feeding devices including a rack mounted on the carriage and a coöperative pinion, of means for adjusting the rack radially of the pinion to vary the relation between the teeth of said rack and said pinion.

22. In a typewriting machine, the combination with a carriage and carriage feeding devices including a rack mounted on the carriage and a coöperative pinion, of means for adjusting the rack radially of the pinion to vary the relation between the teeth of said rack and said pinion, and means for varying the longitudinal relation between said rack and said carriage.

23. In a typewriting machine, the combination of a carriage, carriage feeding devices including a rack, and a mechanical connection between said rack and said carriage, said connection yielding to permit relative movement between said rack and said carriage when the carriage is suddenly arrested during its longitudinal travel in either direction.

24. In a typewriting machine, the combination of a carriage, carriage feeding devices including a rack, and a double acting buffer device connecting said rack with said carriage.

25. In a typewriting machine, the combination of a carriage, carriage feeding devices including a rack, and a connection between said rack and said carriage, said connection comprising a spring and devices by which said spring is compressed when the carriage is suddenly arrested during its longitudinal travel in either direction.

26. In a typewriting machine, the combination of a carriage, a feed rack and a connection between the two adapted to yield when the carriage is stopped in its longitudinal movement in either direction, said connection consisting of an arm fixed at one end to the said feed rack and having an eccentric at the other end, an eccentric strap, an eccentric rod, a rod connected to said eccentric rod and maintained in normal fixed relation with the carriage by a spiral spring.

27. In a typewriting machine, the combination of a carriage, a feed rack adjustably mounted thereon and means for effecting a relative adjustment between the feed rack and the carriage, said means consisting of an arm fixed at one end to the said feed rack and having an eccentric at the other end, an eccentric strap, an eccentric rod, and a rod connected to said eccentric rod and maintained in normal fixed relation with the carriage by a spiral spring.

28. In a typewriting machine, the combination with a carriage of means for stopping the same at a predetermined point, said means consisting of a vertically yielding stop on the carriage, a coöperating stop yielding rearwardly to said carriage stop, and means for stopping said rearward yielding movement.

29. In a typewriting machine, a line lock mechanism comprising a vertically yielding stop on the carriage, a coöperating stop on the frame of the machine yielding rearwardly to said carriage stop, and means for stopping said rearward yielding movement comprising a locking bar and a limiting stop for said locking bar.

Signed at Arlington, in the county of Bennington and State of Vermont this seventh day of April A. D. 1903.

WILLIAM C. FARNUM.
